FRITZ SCHRÖTER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY

METHOD AND ARRANGEMENT FOR AMPLIFYING PHOTOELECTRIC CURRENTS

Application filed March 31, 1928, Serial No. 266,153, and in Germany March 26, 1927. Renewed June 4, 1929.

An application for this invention has been filed in Germany, March 26, 1927, under Serial No. 33,270.

In the telegraphic transmission of pictures it is a good plan to accomplish the amplification of the currents produced in the photoelectric cell, which may be of any desired type or even a selenium cell, by the exploration of the picture in such a manner as to cause the said currents produced to modulate a carrier wave. The carrier is then further amplified and may be sent over the transmission line for wire work or may be arranged to control a wireless transmitter.

In practicing this scheme, several methods are practicable, but among these methods only the three most important ones shall be here named.

(1) After sufficient preliminary amplification, the direct current potential variations furnished from the photoelectric cell are brought to act together with a constant alternating current amplitude of suitable frequency, upon the grid of a socalled compound tube or thermionic tube which acts as a modulator;

(2) The carrier frequency is obtained by applying the alternating current potential (mostly conjointly with a constant direct current potential) directly as the suction or anode potential of the photoelectric cell which is exposed to the light variations incidental to exploration of the picture; and

(3) The carrier frequency results through purely optical means by the rapid interruption of the picture exploring light, for example, by means of a rapidly revolving disk with marginal holes.

Of the above methods (2) and (3) offer the advantage that the complete control or modulation of the carriage wave, i. e., the change from zero to maximum of the amplitude in accordance with the limiting values of dark and light, or black and white in the picture, is constant always, even without strictly accurate electrical adjustments, so that in this way high working safety is insurable. These methods, on the other hand, have so far shown this drawback that they fail to permit direct positive recording of the incoming picture

readily and in all cases. Since the alternating current potential applied to the wire line or used to modulate the wireless transmitter is present only when exploring or scanning bright or light spots in the picture, in the presence of which there is admission of reflected or penetrating light to the photoelectric cell, while for dark spots the alternating current potential drops to zero value. In the arrangements known in the prior art the audio frequency amplifier in the receiver apparatus has been able to furnish current to the picture writing or recording device only as long as the light spots in the outgoing picture came to act upon the photoelectric cell. For instance, when using a picture recorder operating electrochemically and base or predicated upon the passage of current ("blackening" recorder), or the photographic light spot subject to brightness control of a non-reversible light relay arrangement, such as a glow-discharge lamp, then when recording directly on photographic paper in the case of the photographic method, no positive picture was directly obtainable, but only a negative image of the outgoing picture. If with apparatus of this kind, positive recording was directly desired, it was necessary to rectify the alternating current potential at the output end of the amplifier used to reinforce the photoelectric current, and to bring the ensuing direct current potential which is present only in the presence of light upon a separate tone modulating device of the transmitter with an incidental blocking or stopping effect, with the result that audio frequency energy, i. e., recording current, could arise at the receiver end only in the presence of darkness. To be sure, in the case of method (1), according to the sign of the addition of pulsating photoelectric direct current potential and biasing potential at the grid of the thermionic or compound tube, it is possible to effect recording at the receiving end either directly in the form of a positive reproduction or else as a negative. However, this method involves the drawback that the electric adjustment is very delicate, and variations in the sensitivity of the photoelectric cell, the amplitude

of the alternating current potential, the heating and grid biasing potentials, etc., while a transmission is proceeding, cause serious variations in the conditions of complete control or modulation of the carrier frequency. This 5 conduces to difficulties at the receiving end, while at the transmitter end proper manipulation of the modulation means is made difficult.

10 The present invention discloses ways and means whereby direct positive recording at the receiver is made feasible also in the case of the two methods numbered (2) and (3), especially with the latter, even with such 15 means as have before been mentioned, and without an additional reversing device between the photoelectric cell and the transmitter, comprising the rectifier tube in conjunction with another tone modulator of the 20 radio or wire transmitter and controlled in the proper sense by the rectified potential. As a matter of fact, the purpose of such a reversing device according to the present invention, is attainable in a simpler manner by 25 using the carrier frequency, produced by means of a disk with marginal or peripheral perforations or suction alternating current potential at the photoelectric cell, itself for the modulation of the transmitter.

30 The invention consists in that the action of the light upon the exploring photoelectric cell is compensated by the irradiation of a second photoelectric cell with a correspondingly adjusted luminous flux of constant effective 35 value. This luminous flux, for example, may be shunted off from the exploring light beam prior to its striking the picture. As a result, in the presence of a bright spot, and by virtue of balance effected, for instance, in the form 40 of a bridge arrangement, no alternating current modulating the transmitter will arise, whereas in the presence of dark, the compensation is obviated for the reason that the exploring photoelectric cell is then more or less 45 without current, whereas the compensating cell is further illuminated and therefore remains conducting. Hence, audio frequency modulation of the transmitter oscillation or 50 flow of the carrier frequency over the transmission line occurs only when changing to dark in the outgoing picture, and the receiver "blackening" upon the supply of current records directly a positive image of the outgoing picture ("blackening" being broadly 55 understood as the production of a dark picture tone).

55 Figs. 1 and 2 illustrate by way of example embodiments incorporating the basic idea of the present invention, though the scheme is 60 useful not only for picture transmission, but also for other purposes in which light variations are to be recorded by photoelectric cells, and where for the control of the indicator or receiver similar conditions are present as with 65 a picture recorder giving a positive image

only with current. The designations of the parts corresponding in both illustrations are the same, 1 being a constant light source, of which a glow-lamp is suitable although other sources may be used, 2 represents an optical diaphragm provided with a light passage hole of definite size and shape, 3 is a lens arranged to render the light rays coming through the diaphragm 2 from source 1 convergent, 4 is the outgoing picture assumed to be transparent and mounted in the path of the rays from lens 3, 5 and 9 represent the exploring and compensating photoelectric cells, respectively, which are preferably placed to form a bridge arrangement, 6 is a mirror or reflector partly shifted into the path of the rays from lamp 1 for shunting or diverting a definite quantity of light upon another deflection mirror 8 so arranged as to direct the diverted light upon the photoelectric cell 9, 10 is the direct current potential source for the photoelectric current, 11 and 12 represent additional variable direct current potential sources for compensating differences in sensitivity or characteristics of the photoelectric cells 5 and 9, 13 and 14 are the resistance arms of the bridge arrangement, 15 and 16 are diagonal junction points which are brought to the grid and the cathode, respectively, of the amplifier tube 17, and 18, finally, 15 is a variable source of a negative grid biasing potential for the amplifier 17.

If the picture is explored by light reflected from the original to be sent out rather than by passing light, the arrangement, as regards the path of the rays, has to be imagined as being changed correspondingly. In the arrangement shown in Fig. 1, the carrier frequency is produced by inserting in the trajectory of the rays the peripheral row or circle of holes of a rapidly rotating disk 7 which is arranged to interrupt the light from source 1 at the desired frequency. In the case of Fig. 2, on the other hand, the carrier frequency is obtained by providing in series with the direct current potential source 10 an alternating current potential source 19 of any suitable frequency and value. As to the remaining part of the structure, both arrangements are identical in operation. To control the quantity of the light impinging upon the cell 9, instead of shifting the mirror 6 into the ray beam, another arrangement, for instance, an iris diaphragm, a grey wedge cone or the like may be used. What is essential is that the effective quantity of light which is caused to impinge upon the cell 9 is so balanced that in the presence of the brightest shade occurring in the picture 4, no alternating current potential or only a very small one, will arise between points 15 and 16 of the bridge arrangement, and whatever remains can be rendered harmless by suitable stopper means. Apart from having recourse to variations of direct current potentials between 11 and 12, 120

recourse may also be had to varying the resistance conditions in the other arms of the bridge. If, then, owing to a dark spot being touched in the picture, the illumination acting on the cell 5 is momentarily stopped more or less, the balance of the bridge arrangement is disturbed, and the alternating current potential then set up between the points 15 and 16 on the bridge acts upon the grid circuit of the tube 17 which thus furnishes an amplified alternating current potential in the plate circuit. It is this potential that then is put to further use in a way as pointed out in the beginning of the specification.

Having now described my invention, what I claim is:

1. In a system for amplifying varying electric current impulses produced by changes in light intensity, a plurality of photo cells, a record to be transmitted, a light source, means for influencing one of said cells by light from said source varied in intensity in accordance with the variations in light and shade in said record, means for influencing the other of said cells directly from said

light source, whereby said photo cells are subjected to equal light intensities and balanced during the light portions in said record, an amplifier associated with said photo

cells, means for impressing an alternating current frequency upon said cells, means for modulating said frequency in accordance with variations in light and shade reaching the first of said photo cells and means for applying said modulated alternating current frequency to said amplifier during periods of unequal light intensities upon each of said photo cells.

2. In a system for amplifying varying

electrical current impulses produced by changes in light intensity in a record to be transmitted, a pair of photo cells each arranged to form one leg of a bridge structure, means for subjecting one of said cells to varying light intensities in proportion to the intensities of light and shade in a record to be transmitted, means for subjecting the other of said photo cells to a constant illumination whereby for high lights in said record said

cells are balanced, means for introducing an alternating current frequency in said bridge structure, an amplifier connected across one diagonal of said bridge structure, and means provided by an unbalanced condition in said bridge structure due to unequal light intensities upon said cells for applying said alternating current frequency modulated in accordance with said light intensities to said amplifier.

3. In a system for amplifying varying electric current impulses produced by variations in light and shade in a record to be transmitted affecting the amount of light reaching the light sensitive medium, a pair of photo cells, means for subjecting one of

said cells to variations in light intensity in accordance with the light and shade in said record, means for subjecting the other of said photo cells to a constant light intensity, said cells being connected in bridge formation and arranged to each form one leg of said bridge structure, whereby for conditions of maximum light intensity reaching the first of said photo cells said bridge structure is substantially balanced, means provided in the legs of said bridge structure including said cells for compensating for differences in sensitiveness of said cells, means for introducing an alternating current frequency upon said bridge structure, means provided by varying light intensities reaching the first of said photo cells for modulating said alternating current frequency, an amplifier, and means provided by an unbalanced condition in said bridge structure for applying a modulated alternating current frequency upon the input circuit of said amplifier.
